HIS ATTORNEY.

UNITED STATES PATENT OFFICE.

FRANK HINMAN PIERPONT, OF HORLEY, ENGLAND, ASSIGNOR TO LANSTON MONO-TYPE MACHINE COMPANY, OF PHILADELPHIA, PENNSYLVANIA, A CORPORATION OF VIRGINIA.

TYPOGRAPHIC MATRIX-CASE EQUIPMENT.

Application filed February 19, 1924. Serial No. 693,855.

To all whom it may concern:

Be it known that I, FRANK HINMAN PIERPONT, a citizen of the United States of America, residing at Salfords, Horley, in 5 the county of Surrey, England, have invented certain new and useful Improvements in Typographic Matrix-Case Equipments; and I do hereby declare the following to be a full, clear, and exact description 10 of the same, reference being had to the accompanying drawings, forming part of this specification, and to the characters of reference marked thereon.

This invention relates to matrix or die 15 case equipment for type casting and similar typographic machines and refers to matrix cases in which the matrices are assembled in a frame in rows and columns. A matrix case of the kind referred to, as well as a machine 20 in which it is adapted to be employed, is basically disclosed in United States Letters Patent No. 625,998, dated May 30, 1899. In such a matrix case the matrices are oblong blocks, rectangular in cross section, one 25 end being furnished with a character or formative cavity and the other end with a centering cavity usually conical in shape for engagement with a centering device for clamping and pressing each matrix against 30 the mold when a cast is to be made.

The main object of the present invention 35 is to so construct the matrices and the supporting bars therefor that each matrix is separately supported or controlled so that its lateral movements are limited and the accumulated wear of the matrices of a row or column is prevented from allowing the displacement of a single matrix to such an extent as would interfere with its accurate 40 register or presentation to the mold of the machine.

In the present invention the matrices are suspended or supported by a series of parallel bars provided with approximately semi-circular notches or recesses and the matrices are furnished with annular or circular grooves for the reception of the bars whereby each matrix is supported or confined within a circular cell. Other objects of the 45 invention will hereinafter be particularly pointed out or will otherwise appear in connection with the description of the embodiment 50 of two neighboring bars form circular cells or chambers each accommodating a matrix, the shoulders of which above and below the annular groove 7 contact with the

ment of the invention illustrated in the accompanying drawings in which

Fig. 1 is a plan view of a matrix case 55 embodying the present invention,

Fig. 2 is a side elevation thereof,

Fig. 3 is a vertical section on approximately line 3—3 of Fig. 1,

Fig. 4 is a vertical section on approximately line 4—4 of Fig. 1,

Fig. 5 is a horizontal section on approximately line 5—5 of Fig. 3, the matrix case being shown in plan,

Fig. 6 is a plan view of one of the suspension bars, and 65

Fig. 7 is an elevation of one of the matrices.

The matrix case comprises a frame 1, this frame being generally of usual and well-known construction and being box-like in form with an opening through it for the accommodation of the matrices. On the top of the frame 1 is a cover plate 2 provided with a series of perforations or openings 3 coinciding, when the matrices are assembled in the matrix case, with the centering cone holes 4 in the matrices 5 (Fig. 7).

The matrices 5 are oblong blocks, rectangular in cross section and furnished as hitherto with a character or formative cavity 6 in one end and a conical centering cavity 4 in the other end. In accordance with the present invention each matrix is provided with an annular groove 7 of an approximate width and depth to accommodate the suspension bars, this groove forming the cylindrical stem portion 8 of the matrix, as shown in Fig. 7. The suspension bars 9 are provided on each of their side edges with approximately semi-circular grooves or notches 10, the bars being adapted to enter the matrix grooves 7 of two rows of matrices whereby the matrices are supported by the bars, and the notches 10 being provided 85 to accommodate the stem portions 8 of the matrices. The bars 9 are arranged in parallel rows between the rows of matrices so that the opposed edges of two neighboring bars substantially meet (Fig. 5) and the grooves 10 of two neighboring bars form circular 90 cells or chambers each accommodating a matrix, the shoulders of which above and below the annular groove 7 contact with the

bars and cause the bars to support the matrix. The ends of the bars 9 are supported in the end bars 11, 12, which are provided with grooves for the reception of the bars 9. 5 When the matrices 5 and the bars 9 have been assembled, the parts 5, 9, 11, 12 are then placed bodily within the frame 1. The frame 1 is provided with suitable grooves 13, 14, for the reception of the end bars 11, 12, 10 respectively, for the support of the latter. These parts are secured in position within the die case frame by the cover plate 2, the ends of which slide under catches 15, 16, 15 on the ends of the die case frame. The plate 2 is prevented from moving laterally of the die case by slight ridges 17. In order to remove the plate, one edge has to be lifted above one of the ridges 17.

I claim:

- 20 1. A matrix case comprising a frame, matrices therein arranged in a row, each matrix being provided with an annular groove providing a matrix stem portion, and a bar detachably supported in the frame and entering the matrix grooves of the row of matrices to support said row, said bar being provided with lateral, approximately semi-circular notches to accommodate said matrix stem portions.
- 25 2. A matrix case comprising a frame, matrices therein arranged in rows, each matrix

being provided with an annular groove providing a matrix stem portion, and a series of parallel bars detachably supported in the frame, each bar entering the matrix 35 grooves of two rows of matrices, whereby the matrices are supported by the bars, and each bar being provided with lateral, approximately semi-circular notches along each side thereof to accommodate the stem 40 portions of said two rows of matrices.

3. A matrix case comprising a frame, including two removable end bars, matrices in the frame arranged in rows, each matrix being formed with an annular groove providing a matrix stem portion, and a series of parallel bars detachably supported in said end bars of the frame, each bar entering the matrix grooves of two rows of matrices, whereby the matrices are supported by the 45 bars, and each bar being provided with lateral, approximately semi-circular notches along each side thereof to accommodate the stem portions of said two rows of matrices.

4. A typographic matrix comprising a 50 rectangular block provided with a formative cavity in one end and a centering cone hole in the other end, said block being provided intermediate its ends with an annular groove providing a cylindrical stem portion.

FRANK HINMAN PIERPONT.
